UNITED STATES PATENT OFFICE.

JOHN KLEIN, OF DESLOGE, MISSOURI, ASSIGNOR OF TWO-THIRDS TO PAUL A. FUSZ AND CHARLES D. McLURE, OF ST. LOUIS, MISSOURI.

COMBINED CONCENTRATING AND AMALGAMATING TABLE.

SPECIFICATION forming part of Letters Patent No. 760,213, dated May 17, 1904.

Application filed December 3, 1902. Serial No. 133,781. (No model.)

To all whom it may concern:

Be it known that I, JOHN KLEIN, of the city of Desloge, St. Francois county, State of Missouri, have invented certain new and useful Improvements in a Combined Concentrating and Amalgamating Table, of which the following is a full, clear, and exact description, reference being had to the accompanying drawings, forming a part hereof.

10 My invention relates to a combined concentrating and amalgamating table; and it consists of the novel construction, combination, and arrangement of parts hereinafter shown, described, and claimed.

15 In the drawings, Figure 1 is a top plan view of my invention. Fig. 2 is a side elevation of my invention ready for use, parts being broken away. Fig. 3 is a longitudinal mid-section of the same, the wire-gauze above the 20 flooring of the concentrating-table being omitted. Fig. 4 is a transverse section taken on the line $\alpha\alpha$ of Fig. 1. Fig. 5 is a detail view in section, parts being broken away, showing the means by which my invention is 25 supported when in use. Fig. 6 is a detail cross-section showing the opening in which one of the suspending-rods operates.

30 My invention is what might be termed a "concentrating-table" and an "amalgamating-table;" but in reality when my invention is equipped for amalgamating purposes the same table may be used for concentrating purposes; but when I desire to construct my table for concentrating lead ores or any class of ores 35 that contain no free gold I omit certain features of construction, which will be more fully hereinafter described.

40 Referring to the drawings, 1 indicates transverse timbers, and 2 the legs supporting the same, and 3 longitudinal timbers, the said transverse timbers, the longitudinal timbers, and the legs forming the supporting-framework for my table. In this connection I desire to state that any other suitable construction of framework may be employed for supporting the table, as I do not claim in this invention any specific construction by which my table may be supported when in operation.

I will now proceed to describe the construction of the table in detail. The framework of the table is composed of longitudinal side timbers 4, transverse end timbers 5, a longitudinal center timber 6, and transverse center timbers 7, all of which being suitably fastened together so as to form the framework of the table. The framework of the table also has secured to it an upright side piece 8 at the front or top of the table, which is secured in any suitable and mechanical manner. In this connection I desire to state that the framework of my table may be constructed in various ways so as to provide a rigid and solid framework of sufficient strength to stand the jarring, moving, or shaking motion to 50 which the table is subjected while in operation. On top of the framework, as hereinbefore described, a wooden flooring 9 is made, which is secured to the framework in any suitable and mechanical manner. On top of 55 the wooded flooring 9 I cover my table with linoleum or sheet-rubber, and on top of the linoleum or sheet-rubber I place a layer of amalgamated wire-gauze 10, the wire out of which the gauze is made containing about 60 sixty per cent. of copper alloy, and on top of the amalgamated wire-gauze I place a series of copper channels 11. It will be noticed in this connection that I do not graduate my channels; but they all terminate on 65 the same transverse line of the table, (see Fig. 1 for illustration,) thus leaving at the lower end of the table a smooth and unbroken surface α , which is rectangular in dimensions. In addition to the series of copper channels 70 11 I also employ a series of check-blocks 12. These check-blocks are shown as triangular, their apexes extending toward the front or top of the table; but I desire to state in this connection that I can use any shape or dimension of block or any other suitable means to direct, divert, and distribute the pulp. These blocks are preferably made of wood, and it will be noticed in this connection that I use 75 where the slush enters the table a greater number of these blocks than at the point where the clear water passes, because I desire to direct, divert, and distribute the slush and pulp 80 85 90 95

through the blocks, thus completely distributing the feed and concentrating the pulp.

I do not wish to be limited to the precise arrangement, location, and number of blocks 5 12 illustrated in the drawings, as a greater or less number thereof may be employed, and they may be disposed over a greater or less surface of the concentrating-table and relative to the surface occupied by the channels 11, the 10 arrangement shown in the drawings being merely illustrative of one arrangement which I find satisfactory.

The location of the blocks over the surface 15 of the table will completely and effectively distribute, in connection with a jarring, moving, or shaking surface, the substances moving over the surface of the table while in operation at each point where a block is located, by which a greater degree of concentration 20 may be obtained than is now obtained by using continuous or unbroken channels or riffles. These check-blocks 12 are located on top of the amalgamated wire-gauze 10 and are secured to the table by any suitable means. I 25 have found by practical experiments that by using these check-blocks in conjunction with the copper channels or riffles more effective concentration may be obtained than by using continuous or unbroken channels or riffles 30 alone.

I prefer that the channels 11 should be arranged in a direction approximately parallel with the lines of movement of the table and also that the portions of the flooring 9 upon 35 which both the channels and the distributing check-blocks are arranged should be on a common plane.

13 indicates the slush or pulp box, which is mounted over the front or top edge of the 40 table, as illustrated in Figs. 1, 2, and 4, the same being provided with a slush or pulp compartment 14 and a clear-water compartment 15. This box is independent of the concentrating-table, and the operation of the concentrating-table does not in any manner act 45 on the box. Secured to the longitudinal center timber 6 of the framework of the concentrating-table is an H-shaped iron, and secured to the longitudinal center piece of the frame- 50 work on which the concentrating-table is located are right-angular guide-pieces 17. It will be noticed by referring to Fig. 4, wherein this construction is shown, that the H-shaped piece 16 and the pieces 17 constitute a guide 55 by which the table when in operation is prevented from lateral motion.

When the table has been constructed substantially as herein shown and described, it is mounted on the superstructure as follows: Located 60 on each side of the framework and suitably secured thereto are three suspension-standards 18, (three being on each side of the framework,) the base of said suspension-standards being suitably secured to the framework 65 of the superstructure. Pivotedly secured to

the framework of the concentrating-table are rods 19, the ends of which are screw-threaded to receive turnbuckles 20. The ends 21 of the suspension-standards 18 are provided with enlarged openings 22, in which are mounted 70 rods 23, the lower ends of which are screw-threaded to receive the turnbuckles 20. The upper ends of said rods are provided with holes 24 to receive pins 25, by means of which said rods and the parts attached to the lower 75 ends are suspended from the ends 21 of the suspension-standards 18. The enlarged openings 22 are for the purpose of permitting the rods 23 to have a swinging motion, as it is necessary for these rods to swing or move 80 when the table is in operation. The ends 21 of the suspension-standards 18 are secured together by means of transverse rods 26. It will be seen from the foregoing description that my concentrating-table is suspended and 85 may be adjusted at any degree of inclination, that it may be transversely inclined at various angles and longitudinally inclined at various angles, that it is also held from lateral movement, and that by the same being suspended it is easily operated, as the only force necessary to operate the table is to give it a 90 swinging or jarring motion.

When my concentrating-table is constructed as hereinbefore described and mounted as 95 described, I preferably operate it by means of my compressed-air motor patented to me on November 5, 1901, No. 686,087; but I may employ other means for operating the table. I have found from experience that to effect 100 the proper concentration and amalgamation I need a jarring or shaking motion, as a jarring motion facilitates amalgamation and also concentration.

The suspension-standards 18 are laterally 105 braced by means of rods 27.

It will be seen from the foregoing description that the top of my table is provided with a smooth and unbroken surface *a*, so that the water on emerging from the water-box has a 110 clean sweep over said portion of the table in order that any foreign substances of no value may be washed off the table as quickly as possible. The check-blocks 12 I claim as a great benefit to check the current on any jarring, 115 moving, or shaking concentrating-table and, furthermore, as an effective means to direct, divert, and distribute the slush and pulp through the blocks over the table, thus distributing the feed and concentrating the pulp. 120

When I desire to use my table as an amalgamating-table, I amalgamate the copper channels 11 and the wire-gauze 10. This is done in cases where the ores to be treated contain free gold. When I use my table for concentrating lead ores or any class of ores that contain no free gold, I omit, or it is not necessary, rather, to use the amalgamated wire-gauze or to amalgamate the copper channels. However, when my table is equipped as an 125 130

amalgamating-table I can use it without any change for a concentrating-table, if I so desire.

Having fully described my invention, what I claim is—

- 5 1. A combined concentrating and amalgamating table, consisting of a framework, a flooring on the same, a covering for said flooring, an amalgamated wire-gauze located on said covering, a series of ungraduated channels located on said gauze, check-blocks located on the same, means for suspending said table, means for giving said table any degree of inclination, and means for imparting motion to said table, substantially as specified.
- 10 2. The combination of a movable table, a series of ungraduated channels secured to a portion of the upper surface of the table, a feed-trough arranged substantially parallel with the said channels through which the pulp and
- 15 20 water are distributed to the table, and check-blocks carried by the upper surface of the table and arranged between the feed-trough and

the channels, the number of check-blocks being greatest opposite the portion of the trough through which the pulp is fed and less opposite the portion through which the water is fed, substantially as set forth. 25

3. A combined concentrating and amalgamating table having its top surface provided with amalgamated wire-gauze, and a portion 30 of its wire-gauze surface provided with a series of ungraduated amalgamated copper channels, a series of check-blocks and an unbroken, smooth, defined surface at its lower end; means for suspending said table, and 35 means for imparting motion to said table, substantially as specified.

In testimony whereof I affix my signature in presence of two witnesses.

JOHN KLEIN.
